VIBRATOR

Thomas H. Morgan, Dallas, Tex.

Application February 20, 1956, Serial No. 566,518

1 Claim. (Cl. 121—17)

This invention relates to air cushioned vibrators of the inertia type and it has particular reference to vibrators especially useful in supplying the high frequency reciprocating motion necessary in the conveyance and classification of materials, including ores, minerals and the like.

The principal object of the invention is to provide a new and improved pneumatically operated vibrator of the reciprocating type, which is quiet in operation and attains high frequency with minimum air consumption.

Another object of the invention is to provide a vibrator in which a lubricationless piston of the air cushion reverse type is disposed for non-mechanical jet rotation in its cylinder and whose movement in each direction is stopped by an air cushion which renders the operation virtually noiseless.

Another object of the invention is to prevent scoring and to equalize wear of the piston and its cylinder by constantly rotating the piston while it reciprocates in the cylinder under the energy supplied by air under pressure with which both rotation and reciprocation of the piston is accomplished.

Other objects will appear as the description proceeds when considered with the annexed drawing wherein:

In the drawing,

Fig. 1 is a top plan view of the vibrator showing it connected to a shaker frame.

Fig. 2 is a vertical sectional view taken on line 2—2 of Fig. 1;

Fig. 3 is a vertical sectional view taken on line 3—3 of Fig. 1;

Fig. 4 is a horizontal sectional view taken on line 4—4 of Fig. 2;

Fig. 5 is a sectional view taken on line 5—5 of Fig. 3;

Fig. 6 is side view of the vibrator supported on its standards; and

Fig. 7 is a side view of the vibrator.

Referring now to the drawing, the vibrator 20 is shown supported on a pair of side standards 22 which may be substantially triangular in shape and secured at their lower ends to a fixed structure 23. The standards are provided at their upper ends with matching grooved blocks 24 and 25 whose grooves are adjusted to receive the transverse shafts 26 of the vibrator. The blocks 24 and 25 are secured together by bolts 27 which may be loosened to rotate the vibrator about the axis of the shafts 26 to vary the plane of the vibrator as desired.

The vibrator 20 includes a cylinder 30 of cast iron, or other suitable substance whose open ends are closed by heads 31 and 32. The heads also close the open ends of a sleeve 33 which is disposed about but spaced from the cylinder, the side edges of the sleeve being releasably secured by latches 34 secured to one side of the sleeve which engage a head 35 formed at the edge of the adjacent side of the sleeve. The space between the sleeve and the cylinder is filled with fibrous material 36 which acts as a sound absorber for air which escapes from within the cylinder 30 through exhaust slots or ports 37

2

and 38 of the cylinder. A pair of screens 39 are disposed exteriorly of the exhaust ports to prevent the fibrous filler 36 from clogging them.

The heads are securely and rigidly secured to the sleeve in airtight relation by tie bolts 42 and 43 which pass through aligned apertures in the heads, through cylindrical spacers 44 and aligned apertures in a mounting plate 45. Nuts 46 threaded onto the ends of the tie bolts 42 and 43 cooperate with washers 47 to hold 10 the headers, mounting plate and cylinder in rigid relationship.

The inner surface of the cylinder 30 is provided with an internal annular recess or groove 50 into which air under pressure is introduced through an inlet pipe 51 which extends through a suitable aperture in the sleeve 33 and whose open inner end communicates with an inlet port 52 in the cylinder. It will be noted that the inlet pipe and inlet port have a center which is perpendicular to the radius of the piston 55, slidably disposed in the cylinder 40, so that the jet of air passing through the inlet port 52 is projected perpendicularly onto the faces 56 formed by the recesses 57 spaced annularly on the outer surface of the piston sleeve 58. The faces lie in planes radial to the central longitudinal axis of the piston.

25 The piston 55 is formed of the piston sleeve 58 which is made of graphitic substance such as is obtainable under the trade name "Graphitar," and a central steel core 60 which are rigidly connected by an intermediate thick sleeve or layer 60 of type metal or the like. Graphitar 30 is employed for the reason that it obviates the need for oiling and lubrication which is most important where high frequency exhaust impulses are used in concentration applications eliminating removal of oil vapors before used on absorbent permeable substances.

35 The type metal is cast integrally with the outer piston sleeve and the core while the latter are positioned in proper relationship relative to one another. The outer piston sleeve has an internal flange 62 while the core has annular grooves 63 which, once the type metal has solidified, prevent longitudinal movement of the outer sleeve relative to the core.

40 The ring of recesses 57 of the piston is positioned in substantial alignment with the annular recess 50 of the cylinder. The outer piston sleeve is also provided with a pair of annular outer recesses 66 and 67 disposed on opposite sides of the recesses 57 and so dimensioned or spaced that when the piston moves longitudinally and the outer recess 66 or 67 is in communication or alignment with the annular recess 50 of the cylinder, the other is out of alignment or registry therewith and vice versa.

45 The piston is provided with a plurality of air passages 68 which communicate with the outer recess 66 and open at the end of the piston adjacent the header 32. A plurality of similar air passages 69 communicate with the outer recess 67 and open at the end of the piston adjacent the header 31.

50 It will now be apparent that if air under pressure is projected into the annular recess 50 through the inlet pipe 51 and port 52 and directed onto the faces 56, the force of the air impelled onto the faces will cause the piston to rotate about its longitudinal axis. The air will then flow in the annular recess 50 and into the annular outer recess 66 or 67 of the piston which is in registry with the cylinder recess 50. For example, if the piston is in the extreme left position shown in Fig. 3, the air flows into the outer piston recess 67 and then through the passages 69 of the piston into the cylinder between the header 31 and the left end of the piston. Since the exhaust port is now open to atmosphere, the air moves the piston to the right which movement closes the exhaust port 37 and opens the exhaust port 38 to atmosphere. After the closing of the exhaust port 37, the

momentum of the piston continues its movement until the enclosed body of air in the right hand end of the cylinder is compressed sufficiently to negative the force of momentum. Its movement is then reversed by the expansion of the air which was thus compressed and by the air from the air inlet 51, since when the piston approaches the header 32, the outer piston recess 67 is moved out of registry with the cylinder annular recess and the outer piston recess 66 is moved into such registry and since the exhaust port 39 is then opened. This 10 operation alternately reciprocates the piston.

In order to insure that the piston 55 be at an extreme position or off center at the start of operations, the header 31 may be provided with an inlet port 76 equipped with a check valve 71 whereby air under pressure may be admitted to the left end of the cylinder through a flexible hose 71a to move the piston to the right to an off center position so that when air is then admitted through the inlet port 52, the piston will move to the left initially and gather sufficient momentum to cause reciprocating movement thereof to be sustained. 15

It will be noted that the piston will rotate constantly so that scoring of the piston and cylinder will be minimized while wear thereof will be equalized over their full annular surfaces thus prolonging the life of the vibrator and decreasing the required maintenance.

Longitudinal movement of the vibrator 20 is permitted by the mounting thereof by means of a supporting rectangular frame 75 rigidly secured to the transverse shafts 26. The rectangular supporting frame has aligned pairs of apertures in its end members 76 and 77 through which extend the mounting bolts 78. The mounting bolts 78 extend through aligned apertures in the headers 31 and 32 and through spacer sleeves 79 and 80 whose adjacent flanged ends bear against the headers 31 and 32, respectively. 30

The spacer sleeve 79 is slidably supported in oilite sleeve bearings 81 carried by sleeves 82 threaded in dust caps 83 which are rigidly mounted on the end member 76 of the supporting frame by means of bolts 84 passing through suitable apertures in the end member and the flanges 85 of the dust caps. 40

A spring 88 which extends about the spacer sleeves 79 bear against the end flanges 89 thereof and against washers 90 which bear against the sleeves 81 and 82 bias the spacer sleeve 79 and therefore bias the vibrator toward movement to the right. A corrugated cylindrical dust cover 91, which may be of rubber, extends over the spring 88, the end flanges 89 and rings 92 to protect the springs 88 and the spacer sleeves 79 from foreign matter. The rings 92 are mounted on the end member 76 by bolts 84 which extend through flanges 93 of the rings. 45

The spacer sleeves 80 are slidably supported in oilite sleeve bearings 94 carried by sleeves 95 which are rigidly mounted on the end member 77 of the frame by means of bolts 96 which pass through suitable apertures in the annular flanges 97 of the sleeves 95. 55

Springs 98 which extend about the spacer sleeves 80 bear against the end flanges 99 of the spacer sleeve 80 and against washers 100 which bear against the sleeves 95 and therefore bias the vibrator toward movement toward the left. Corrugated cylindrical dust covers 102, which may be of rubber, extend over the springs 98, the end flanges 99 and rings 103 to protect the springs 98 and spacer sleeves 80 against foreign matter. The rings 103 are mounted on the end member 77 by means of the bolts 96 which extend through annular flanges 104. 60

The outer ends of the spacer sleeves 80 abut the inner surface of the mounting plate 45 while the mounting bolts 78 extend beyond the spacer sleeves 80 through member 106 of a shaker platform or tray 107. Nuts 108 on the threaded ends of the mounting bolts hold the cylinder 30, the spacer sleeves 79 and 80, the mounting plate 45 and the shaker frame 107 in rigid relation. 70

ship so that these elements move longitudinally as a unit under the influence of the movement of the piston.

The outer ends of the spacer sleeves are provided with end sleeves 109, secured thereto by set screws 110. Corrugated dust covers 111 extend over the end sleeves 109 and the sleeves 95 to protect the outer ends of the spacer sleeves. It will be apparent that the various corrugated covers may be bonded to their supporting elements by use of an adhesive.

It will now be seen that reciprocating movement of the piston 55 will result in reciprocating movement of the cylinder 30 together with all of the elements rigidly assembled thereon or therewith. For example, if the piston 55 moves to the right, the air compressed between the right end of the piston and the header 32 will impart a force to the header 32 which will tend to move the spacer sleeve 80 toward the right against the resistance of the spring 98. As a result, the mounting plate 45 and the shaker frame 107 will also move to the right. When the direction of movement of the piston is reversed to the left, the air compressed between the left end of the piston and the header 31 will impart a force to the header 31 which will tend to move the spacer sleeve 79 toward the left against the resistance of the springs 88. 25 As a result the mounting plate 45 and the shaker frame 107 will now move toward the left. The supporting frame 75 of the vibrator, of course, remains stationary, since it is rigidly mounted on the standards 22. The springs 88 and 98 keep the cylinder assembly centered between the end members 76 and 77 thereof.

It will be apparent now that a new and improved vibrator has been described and illustrated wherein the piston 55 is not directly and rigidly connected to the shaker 107 and that the reciprocating movement of the piston transmits forces through the agency of a compressible fluid, such as air, to the cylinder assembly in which the piston moves, the cylinder assembly being rigidly connected to the shaker. It will also be apparent that the activating fluid not only causes reciprocating movement of the piston but also rotary movement whereby scoring of the piston and cylinder is minimized. Moreover it will be apparent that the plane of the vibrator may be easily changed by loosening the bolts 27, pivoting the vibrator frame 75 about the shafts 26 to the desired plane or angle and then tightening the bolts 27.

It will be further seen that the vibrator will be substantially noiseless due to the cushioning effect of the air caught between the ends of the piston and the headers so that the piston never strikes the headers during operation, and due also to the exhaust silencing (see column 1, lines 70, 71, 72 and column 2, lines 1, 2 and 3).

The frequency of vibration can be controlled by proper dimensioning of the piston, the greater the mass of the piston in relation to its cross-sectional area, the lower the frequency of vibration. The length of the piston, of course, influences the mass, so that the piston is made shorter where higher frequencies of vibration are desired and longer where lower frequencies are desired. It has been determined that highest inertia forces relative to frequency are attained by so forming the piston that its diameter will equal or almost equal the length thereof, since negative results are known to obtain where the length is greater than the diameter.

Manifestly, the construction as shown and described is capable of some modification and such modification as may be construed to fall within the scope and meaning of the appended claim is also considered to be within the spirit and intent of the invention.

What is claimed is:

A vibrator including a cylinder and a piston reciprocable therein, said cylinder and piston having coating ports and passages operable to supply fluid to the cylinder to reciprocate the piston to produce vibrating motion; and means on the piston acted on by the fluid for producing rotation of the piston in the cylinder about an axis

parallel to the reciprocable movement of the piston, support means for said cylinder permitting limited reciprocal movement of said cylinder relative to said support means in a direction parallel to said axis, and means for connecting said cylinder to a structure which is to be vibrated, and means adjustably pivotally mounting said support means on a fixed structure, whereby said support means may be pivotally adjusted about an axis perpendicular to the reciprocable movement of the piston.
